UNITED STATES PATENT OFFICE.

ACHILLE J. PELLETIER AND FERNAND BÉLISLE, OF OTTAWA, ONTARIO, CANADA.

COMBINED SWITCH AND FUSE.

1,321,390.

Specification of Letters Patent. Patented Nov. 11, 1919.

Application filed March 22, 1918. Serial No. 224,047.

To all whom it may concern:

Be it known that we, ACHILLE JOSEPH PELLETIER and FERNAND BÉLISLE, citizens of Canada, residing at Ottawa, in the county 5 of Carleton, in the Province of Ontario, Canada, have jointly invented certain new and useful Improvements in Combined Switches and Fuses, of which the following is a specification.

10 This invention relates to a combined switch and fuse having a detachable connecting element carrying one or more enclosed renewable fuses.

The object of the invention is to provide a 15 switch, cut out or similar device having enclosed renewable fuses, carried by a readily detachable carrier which is adapted to be engaged with and disengaged from the stationary contacts for closing and opening 20 the circuit. The arrangement is such that the fuses are readily accessible and may be renewed with absolute safety by unskilled persons, while being so attached, and they may be quickly removed from and inserted 25 in place after a fuse has "blown."

To these ends this invention consists of an electric switch and of the construction, arrangement and combination of the parts thereof as hereinafter described, and more 30 particularly pointed out in the claims at the end of this specification.

In the accompanying drawings, Figure 1 is a perspective view of a two wire circuit switch, showing an improved method of closing and mounting a fuse or fuses on the 35 detachable arm of the switch, embodying our invention; Fig. 2 is a side view of the switch; Fig. 3 is a longitudinal section of a single fuse carrier, showing the fuse secured thereto as adapted for use with switches for 40 one, three, five and other odd numbered wire circuits; Fig. 4 is a front view of a fuse carrier provided with two fuses, the casing being removed; Fig. 5 is a side view of a double 45 fuse carrier showing one fuse in position and an expansion chamber in association therewith; Fig. 6 is a view of the casing showing contact plates projecting interiorly and exteriorly thereof; Fig. 7 is a detail of 50 a bracket member; Fig. 8 is a detail of the locking member; Fig. 9 is a view of a modified construction of a one-way supporting bracket; Fig. 10 is a detail of the locking member as shown in Fig. 9; Fig. 11 is a 55 view of a two way supporting bracket.

In the different figures of the drawings

the same reference character is used to identify the same element.

Referring to the drawings and the characters of reference which appear thereon, 1 designates a suitable base of insulating material, upon which the switch is mounted. Near one end of the said base are secured the contact plates 2 having binding screws 3 for the main circuit wires. Near the opposite 60 end of the base are the contact plates 4, provided with binding screws 5 by which the branch circuit wires are secured to these contacts.

Mounted on the base is a substantially 70 U-shaped bracket 6, each arm of which is provided with an open slot 23 adapted to accommodate a pin 19 carried by the arm or connecting element 9. The bracket 6 has a base 24 adapted to be secured to the switch 75 base 1 by means of screws 25, and each arm near this base is provided with a hole or opening 26. Mounted on the bracket 6 is a double bell crank lever 7 pivoted at the angle and having one pair of arms projecting 80 across and beyond the slot openings, so as to coöperate with the pin 19, thereby detachably maintaining the arm or connecting element in engagement with the bracket 6.

The lever 7 as shown in Fig. 8 is formed 85 from a single piece of wire which is first bent hair pin shaped, the two legs then being bent outwardly at a point about one third the distance from the bight 27 as shown at 28, and in the same horizontal 90 plane—as herein illustrated—as the bight of the hair pin, these portions being again bent at right angle to the arms 28 and extending in the same vertical plane as these latter. The portions 28 are adapted to project 95 through the holes or openings 26, and by their coöperation with the periphery of these holes constitute a pivot for the bell crank. A spring 8 has one end attached to the bight 27 of the lever 7 and its opposite end 100 to the base 1, so that this locking member is resiliently retained in operative position. Coiled springs surrounding the portions 28 and secured thereto and to the bracket 6 could be substituted for the spring 8. This 105 being a well known alternative arrangement it is not illustrated. Moreover the bracket could be placed with the open slots directed upwardly, that is, in the reverse position to that shown in Fig. 2. In this case the spring 110 would be positioned below the bracket 6 as shown in Fig. 9, or the locking device could

be dispensed with. In either arrangement the arm 9 may be readily attached to and detached from the bracket 6, and would be securely held when in operative position.

- 5 The base is provided with a pair of spring finger clamps 10 to hold the connecting element in a non-contacting position when desired, also to effect a snap action when said element is moved from the position shown 10 in Fig. 2 to circuit closing position, and to retain said element in the latter position.

The arm or connecting element is made of insulating material and in two parts, the inner or fuse carrier 13, and the outer or inclosing casing 11. Preferably both are circular in cross section and so designed that the carrier fits tightly within the casing. The carrier is provided with slots 14 extending from one end almost to the other, 20 and has an expansion chamber 17 intermediate between the ends of the slots. The inclosing casing carries a pair of contact plates 12 at diametrically opposite points near each end which project through and extend inwardly from the inner surface of the casing wall.

The inclosing casing is adapted to slide endwise over the carrier 13; the inner projecting portions of the contact plates traversing the slots 14, and being thereby guided to engage the fuse or fuses at points spaced apart longitudinally thereof.

The inner projecting portions of the contact plates are of such length that they firmly bind the fuse or fuses between them and the carrier, at the points of contact when the casing is slid home. One end of the fuse is inserted in the slots or recesses 16 in the carrier so as to retain them in position.

- 40 The fuse carrier 13 which is made of non-conductive material, is provided with an expansion chamber 17 on each fuse support in juxtaposition to the fuse when in position. A rod 18 passes centrally through the carrier 45 and projects beyond each of its ends, carries a pin 19 at one end by which it is pivotally secured to the bracket 6, and is screw threaded at the other end to receive an internally threaded cap or nut 20, adapted 50 to force the casing into engagement with the projection 21. Between the projection 21 and the end of the casing a washer 22 is interposed to produce a gas tight joint.

The design shown in Fig. 9 differs from 55 that hereinbefore described in the form of the locking element and the mode of mounting it relatively to the bracket 6. The element 7 is substantially U shaped and is applied from the back of the switch base, its 60 arms projecting through slots provided in the base. The spring 8 is secured to the rearwardly directed position of the lever and the rear face of said base.

The design of the bracket shown in Fig. 65 11 is adapted to support a pair of switch

arms 9, and is of the modified construction set forth in Fig. 9.

In a switch for a two wire circuit the carrier is designed to receive two fuses as shown in Fig. 4, and the body of the carrier is dimensioned to engage the casing tightly between the fuse slots 14 and expansion chamber 17, so that the arc from one fuse which has blown will not injure the other.

This invention is applicable to switches 75 for use with circuits of any number of wires, and also to two way or double throw switches. The stationary contacts may be of any design, as may also the fusible conductors, which may be held in position on 80 the carrier by any suitable means which will not interfere with the assembly of carrier and casing.

The operation of our switch is clearly set forth in the preceding portion of this description. To replace a fuse that has blown, the connecting element is rotated about the pivotal joint formed by the bracket 6 and the pin 19, so that the contacts 12 are disconnected from the stationary contacts 2 and 4, is then detached from the bracket 6, the cap or nut unscrewed, and the outer casing removed. A new fuse having been secured in position on the carrier—the arms 7 being in the position shown in dotted lines in Fig. 2,—the casing is slid thereover into position and the cap or nut is screwed up tight on the rod 18. The pin 19 of the connecting element is engaged with the lever 7 which is oscillated against the action of the spring 8 so as to uncover the slots in the bracket 6, the pin is free to enter said slots, and the arm is afterward rotated into position with the contacts 12 engaging the contacts 2 and 4 on the base. The spring 100 clamps 10 are offset intermediate of their length to snap said connecting element into operative position.

A switch designed as hereinbefore described, combines the advantages of a knife 110 switch or cut out and a fuse block, since the contacts are as effective as a knife blade, the break in the circuit is as positive, and the fuse is inclosed in a casing and interposed 115 between movable contacts mounted on said casing.

From this it will be seen that we have devised a very simple and effective switch which may be economically manufactured, embodies both the switching and protective 120 function, is durable in construction, is fool proof and the insulated fusible conductors are more readily placed in and removed from position than in other switches of this class.

125 It is fool proof since no tools are employed in effecting renewals, hence the danger of short-circuiting the line, or shocking the person making renewals is absolutely eliminated, by virtue of the fact that the 130

switch arm is entirely removed from the live contacts.

A switch of this type is therefore simple, effective and safe.

- 5 We are aware that changes could be made in the arrangement, relation and combination of the parts entering into our construction within the spirit of our invention, the preferred construction of which we have 65
10 herein described. Consequently we do not wish to be limited by this disclosure, but claim all the modifications and equivalent constructions coming within the scope of the appended claims.
- 15 What we claim and desire to secure by Letters Patent is:

1. A cut-out comprising a base, contacts thereon, an arm carrying a fuse to connect said contacts, a bracket, means on the arm 20 detachably engaging said bracket, and resiliently controlled locking means to secure said arm to the bracket, substantially as described.

2. A cut-out comprising a base, contacts 25 thereon, an arm carrying a fuse to connect said contacts, a pin secured to said arm, a bracket provided with slots, the pin adapted to be entered into said slots and coöperating with the bracket to constitute a pivot-joint, 30 and locking means to retain said pin in said slots, substantially as described.

3. A cut-out comprising a base, contacts thereon, an arm carrying a fuse to connect said contacts, a separable pivot-joint to connect said arm to the base, and spring controlled locking means for said joint, substantially as described.

4. A cut-out consisting of a base, contacts thereon, an arm comprising a fuse carrier, a 40 fuse thereon, means detachably secured thereto having contacts engaging said fuse and adapted to engage said first mentioned contacts, and means separate from said first mentioned contacts to secure said arm to the base, and locking means for said securing 45 means, substantially as described.

5. A cut-out consisting of a base, contacts thereon, an arm comprising a fuse carrier, a fuse thereon, means detachably secured 50 thereto having contacts engaging said fuse and adapted to engage said first mentioned contacts, and means separate from said first mentioned contacts to detachably secure said arm to the base, and locking means for said detachable securing means, substantially as described.

6. A cut-out consisting of a base, contacts thereon, an arm comprising a fuse carrier, a fuse thereon, means detachably secured 60 thereto having contacts engaging said fuse

and adapted to engage said first mentioned contacts, and means separate from said first mentioned contacts pivotally securing said arm to the base, and locking means for said pivotal securing means, substantially as described. 65

7. A cut-out consisting of a base, contacts thereon, an arm comprising a fuse carrier, a fuse thereon, means detachably secured thereto having contacts engaging said fuse 70 and adapted to engage said first mentioned contacts, and means separate from said first mentioned contacts detachably and pivotally securing said arm to the base, and locking means for said securing means, substantially as described. 75

8. A cut-out consisting of a base, contacts thereon, an arm comprising a fuse carrier, a fuse thereon, means detachably secured thereto having contacts engaging said fuse 80 and adapted to engage said first mentioned contacts, a bracket and means engaging said bracket for securing said arm to the bracket, and locking means for said securing means, substantially as described. 85

9. A cut-out consisting of a base, contacts thereon, an arm comprising a fuse carrier, a fuse thereon, means detachably secured thereto having contacts engaging said fuse and adapted to engage said first mentioned contacts, a bracket and means detachably engaging said bracket for securing said arm to the bracket, and locking means for said detachable securing means, substantially as described. 90

10. A cut-out consisting of a base, contacts thereon, an arm comprising a fuse carrier, a fuse thereon, means detachably secured thereto having contacts engaging said fuse and adapted to engage said first mentioned contacts, a bracket and means pivotally engaging said bracket for securing said arm to the bracket, and locking means for said pivotal securing means, substantially as described. 100

11. A cut-out consisting of a base, contacts thereon, an arm comprising a fuse carrier, a fuse thereon, means detachably secured thereto having contacts engaging said fuse and adapted to engage said first mentioned contacts, a bracket and means detachably and pivotally engaging said bracket for securing said arm to the bracket, and locking means for said securing means, substantially as described. 110
